UNITED STATES PATENT OFFICE.

CHARLES H. AGNE, OF NEWARK, NEW JERSEY.

ORCHESTRA-BELLS.

SPECIFICATION forming part of Letters Patent No. 742,952, dated November 3, 1903.

Application filed May 31, 1902. Serial No. 109,635. (No model.)

To all whom it may concern:

Be it known that I, CHARLES H. AGNE, a citizen of the United States, residing in the city of Newark, in the county of Essex and State of New Jersey, have invented a certain new and useful Improvement in Orchestra-Bells, of which the following is a full, clear, concise, and exact description, reference being had to the accompanying drawings, forming a part of this specification.

My invention relates to an improvement in orchestra-bells, and the object is to produce an aluminium bar, preferably channel-shaped, which will produce an exceptionally fine tone.

While the essential and characteristic features of my invention are necessarily susceptible of modification, the preferred embodiment of the invention is illustrated in the accompanying drawings, in which—

Figure 1 represents an orchestra-bells embodying my invention. Fig. 2 represents a side elevation of the same. Fig. 3 represents a sectional end view taken on lines *xx* in Fig. 1. Fig. 4 represents a plan view of my improved bar. Fig. 5 represents an end elevation of the same. Fig. 6 represents a side elevation of the same, and Figs. 7, 8, and 9 represent modified forms of the bar.

Similar letters of reference indicate corresponding parts in the several views.

a represents a musical instrument of the type known as "orchestra-bells," consisting of a felt-covered supporting-frame *b*, upon which are mounted a series of aluminium bars *c*.

After exhaustive and expensive experiments I have discovered that the bars *c* when made of aluminium produce when operated upon in the usual manner a tone far superior to those made of steel, which heretofore have been exclusively used. The preferred form of bar shown in Figs. 4, 5, and 6 is channel or **U** shaped in cross-section and is preferably made out of sheet-aluminium of the re-

quired quality cut to the required width and then bent downward in order to form the sides *d d*; but the bar may be cast solid and the groove in the under side can be milled or cut out with an ordinary milling or cutting tool, or, if preferred, the bar can be cast with the bosses *e* on the under side of the bar, which bosses form or constitute a long bear-

ing for the spacing-pins *f*, which are secured to the felt-covered frame *b*. The pins *f* are secured to the supporting-frame *b* in any well-known manner and form a spacing means for the bars *c* and at the same time keep them in operative relation with each other when operated upon. The bars *c* can be and are usually made with or without the bosses *e*, (see Fig. 7,) the principal advantage of the boss being to prevent the bar when struck an unusually hard blow from disengaging itself from the pin *f*. I have shown a modified form of bar in the form of a tubular bar, (see Fig. 8,) which also produces exceeding fine tones.

It will be observed that the channel or **U** shaped construction of my aluminium bar presents less bearing-surface for the bar to rest on the supporting-frame than those heretofore employed which were made of solid steel and in which the entire width of the bar rests on the supporting-frame. My construction aids materially in producing a clear, mellow, and exceedingly fine musical tone which has been foreign in the steel bars heretofore employed in musical instruments of the class herein described. It will also be observed that the weight of my improved bar is materially less than the steel bars heretofore used for similar purposes—a fact which is of great importance, considering that the instruments on which the bars rest are portable and are carried about from place to place, and the number of bars usually employed range from eighteen to thirty.

Having described my invention, what I claim is—

1. In an instrument of the class herein described, the combination of a series of aluminium oblong bars **U**-shaped in cross-section, bosses on the under side of said bars for the reception of spacing means, a supporting-frame and means for spacing said bars on said frame, substantially as described.

2. In an instrument of the class herein described, the combination of a series of cast-aluminium oblong bars **U**-shaped in cross-section, bosses on the under side of said bars for the reception of spacing means, a felt-covered supporting-frame, and means for spacing said bars on said frame, substantially as described.

3. In an instrument of the class herein described, the combination of a series of aluminium oblong bars **U**-shaped in cross-section, bosses on the under side of said bars for the reception of spacing means, holes in the side wall of said bars for the reception of a tape for maintaining the bars on the frame to prevent the bar from accidental displacement from the frame, a felt-covered supporting-frame and means for spacing said bars on said frame, substantially as described.

4. In an instrument of the class herein described, the combination of a series of oblong aluminium bars, grooved longitudinally on their under side, a supporting - frame and means for spacing said bars on said frame, substantially as described.

5. A musical instrument consisting of a felt - covered frame, a series of oblong aluminium bars **U**-shaped in cross-section, and a curved upper surface, bosses on the under

side of said bars for the reception of spacing means, and means for spacing said bars on said frame, substantially as described.

6. A musical instrument consisting of a ²⁵ felt-covered frame, a series of cast-aluminium bars **U** -shaped in cross - section, and a curved uppersurface mounted on said frame, bosses on the under side of said bars for the reception of spacing means, holes in the side ³⁰ walls of said bars for the reception of a tape for maintaining the bars on the supporting-frame to prevent accidental displacement from the frame, and means for spacing said bars on said frame, substantially as de- ³⁵ scribed.

This specification signed and witnessed this 29th day of May, 1902.

CHARLES H. AGNE.
